UNITED STATES PATENT OFFICE.

JULES CAUDERAY, OF LAUSANNE, SWITZERLAND.

ELECTRIC TIME-SWITCH.

No. 897,585.

Specification of Letters Patent. Patented Sept. 1, 1908.

Application filed February 4, 1907. Serial No. 355,606.

To all whom it may concern:

Be it known that I, JULES CAUDERAY, electrician, a citizen of the Republic of Switzerland, residing at Lausanne, Canton de Vaud, Switzerland, have invented certain new and useful Improvements in and Relating to Electric Time-Switches, of which the following is a specification.

My invention relates to an improvement 10 in controlling apparatus for electric circuits, and more specifically to a time switch or other apparatus for closing and opening an electric lamp circuit at predetermined hours, the lamps of the circuit being thereby automatically lighted and put out at the predetermined hours.

In the drawing, Figure 1 illustrates the apparatus with one of its dials and a part of the cover of a box containing the mechanism re- 20 moved. Fig. 2 shows a part of the dial of the apparatus, and Figs. 3 and 4 are detail views.

The apparatus comprises a clock movement *a*, the small hand of which makes one revolution in twenty-four hours. This clock movement actuates a toothed wheel *b* also making one revolution in twenty-four hours. I also employ two other toothed wheels, both engaged with and of the same size as the wheel 30 *b*, and carried respectively by arbors *c'*, *c''* on each of which an index or a hand *d* is mounted. Moreover, each arbor *c'* and *c''* carries a disk *e*,—the rear face of which is shown in Fig. 4,—provided with a barrel *e'* which is 35 adjusted by friction upon its arbor *c'* *c''*, in order that the position of the divisions drawn on the front face of the disk may be adjusted to any position desired in relation to the corresponding hand *d*. On the rear face of each 40 disk there is a cam *e''* adapted to engage a pin carried by an arm *f'* of a sector *g'*, or an arm *f''* of the sector *g''*, these sectors both being loosely mounted on a shaft *h*. The sectors *g'* and *g''* are subjected to the action of springs 45 *i*, causing the pins of the arms *f'* and *f''* to bear against the faces of the cams *e''*. These cams *e''* are so shaped and placed on the rear face of the disks that they progressively move the arms *f'* and *f''* from the arbors *c'* 50 and *c''* and approach the same under the action of the springs *i* when the hands of the clock movement *a* point to the hour indicated by the index *d* on the dial of either of the disks *e*. The sectors *g'* and *g''* each carry 55 a pawl *k* engaging the teeth of a ratchet wheel *l* secured on the shaft *h*. A starwheel *m* (Fig. 3)

is also secured on the shaft *h*, the circumference of which is serrated, thereby providing a series of projections and intermediate depressions. The circumference of the wheel *m* is 60 engaged by a projecting part of a flat spring *n* carried by a terminal connected to the circuit which is to be controlled by the apparatus. This spring *n* is so formed that its free end is brought into contact with a screw *o* 65 carried by another terminal of the circuit to be controlled by the apparatus, when the projecting part of the spring rests on the top of one of the projections of the circumference of the wheel *m* as shown in dotted lines in 70 Fig. 3. The said end of the spring is removed from the screw *o* and opens the circuit between the two terminals, when the projecting part of the spring rests in a depression between two projections as shown in 75 full lines in Fig. 3. On the shaft *h* moreover is secured a ratchet wheel *p* with the teeth of which the extremity of a catch spring *q* engages.

r is a spring corresponding with the spring 80 *n* and the projecting part of which rests on the top of a projection of the circumference of the wheel *m* when the projecting part of the spring *n* rests in a depression between two projections of the wheel *m* in order to 85 assure the regular movement of the wheel.

The cams *e''* are made in such a manner that the extent of the movement given to the arms *f'* and *f''*, when these approach the shafts *c'* and *c''* after having been moved 90 away from these shafts by the cams, is such, that each partial rotation imparted to the wheel *m* turns this wheel sufficiently to cause the projecting part of the spring *n* to pass from the top of one projection on the circumference of the wheel *m* into the adjacent depression or from a depression to the top of the next succeeding projection. 95

The operation of the hereinbefore described apparatus is as follows:—Assuming 100 the different parts of the apparatus are given the positions shown in the drawing, and the clock movement running normally, the two disks *e* are placed so that one of the hands *d* points to the hour at which the closing of the 105 electric circuit is desired, and the other hand points to the hour at which the circuit is to be opened. Now as the wheel *b* turns the wheels meshing with it, and these wheels together with the disks *e* and the cams *e''* are 110 carried by the shafts *c'* and *c''* respectively, when the hour has come at which the closing

of the circuit is to be effected, the disengagement of one of the arms f' , f'' , will be caused by the cam acting thereon. By means of one of the pawls k and the ratchet wheel l , this arm will cause in its turn a partial rotation of the wheel m , thereby moving the spring n and closing the circuit. Obviously too, when the hour has arrived at which the opening of the circuit is desired, the other arm will cause in the same manner, the wheel m to be partially but sufficiently rotated to open the circuit. If the clock movement is provided with a motor which will run the movement for several days without rewinding, and if, also the positions of the disks e are not changed, the closing and opening of the circuit will take place at the same hours on each and every day, so long as the clock movement runs.

20 I claim as my invention:

1. A time switch mechanism comprising a motor, a shaft, means actuated by said motor for imparting intermittent partial revolutions to said shaft at predetermined and regulatable intervals, a star wheel on said shaft, terminals, and a pair of springs connected to one of said terminals, and adapted to bear against the periphery of the said wheel alternately the one against the point of a tooth and the other against the surface intervening between two teeth thereof, and to be actuated thereby to close an electric circuit through the other terminal and to control movement of the star wheel.

35 2. A time switch mechanism comprising a motor, a pair of arbors, a disk on each of said arbors driven simultaneously by said motor, a cam on each of the said disks, a shaft, sector members mounted independently on said shaft, an arm secured to each sector member, a pin in each arm and adapted to contact with the face of one of said cams, means for maintaining the said pins in contact with said cams, a ratchet wheel on said shaft, a pawl on each of said sector members adapted to engage the said ratchet, a star wheel on said shaft, a spring actuated by said star wheel to open and close an electric circuit, and a spring for limiting each movement of the 50 said star wheel.

3. A time switch mechanism comprising a motor, a disk, an arbor on which the same is mounted, a cam on said disk, a shaft, means actuated by said cam for imparting intermittent partial rotations to said shaft, terminals, a spring connected at one end to one o

the said terminals and adapted at its other end to contact with the other terminal and means on the said shaft for directly actuating the said spring to open and close an electric 60 circuit.

4. A time switch mechanism comprising a motor, a disk, an arbor on which the same is mounted, a cam on said disk, a shaft, means actuated by said cam for imparting intermittent partial rotations to said shaft, terminals, a pair of springs each connected at one end to one of said terminals and each adapted at its other end to make electrical contact with the other terminal and means fixed on said shaft for directly and simultaneously actuating both said springs to open and close an electric circuit.

5. A time switch mechanism comprising a motor, a disk, an arbor on which the same is mounted, a cam on said disk, a shaft, terminals, a pair of springs each connected at one end to one of said terminals and each adapted at its other end to make electrical contact with the other terminal, a star-wheel fixed to said shaft and provided with an uneven number of points adapted to bear against each of the said springs to open and close an electric circuit and means actuated by the said cams for imparting intermittent partial rotations to the said shaft and star-wheel.

6. A time switch mechanism comprising a motor, a disk, an arbor on which the same is mounted, a cam on said disk, a shaft, terminals, a pair of springs each connected at one end to one of said terminals and each adapted at its other end to make electrical contact with the other terminal, a star-wheel fixed to said shaft and provided with an uneven number of points adapted to bear against each of the said springs to open and close an electric circuit, a sector member loosely mounted on the said shaft, an arm secured in the sector member and adapted to be engaged by the said cam, a ratchet fixed on the said shaft, a pawl secured on the said sector member and adapted to engage the teeth of the said ratchet and means for maintaining the said arm in contact with the surface of the said cam.

In testimony whereof I have affixed my signature in presence of two witnesses.

JULES CAUDERAY.
